UNITED STATES PATENT OFFICE

2,064,634

ELECTRICAL HEATING SYSTEM

John C. Sharp, Oak Park, Ill., assignor to Edison
General Electric Appliance Company, Chicago,
Ill., a corporation of New York

Application October 23, 1934, Serial No. 749,544

3 Claims. (Cl. 219—20)

This invention relates to electric heating systems, more particularly to heating systems for electric cooking appliances, such as electric ranges, and it has for its object the provision of an improved system of this character providing various rates of heat generation.

This invention is particularly applicable to heating systems for electric range surface units and the like, wherein a supply source is used having two voltages, such as a three-wire source wherein the voltage between the two main wires is twice as great as that between each main wire and the neutral, for example, 230 volts between the main wires and 115 volts between each main wire and the neutral. Heretofore, in systems of this character, it has been the practice to use a heating unit having two heat generating resistance elements. These resistance elements are connected to the supply source in such manner as to give three wattage combinations, which provide high, medium and low heats. In the systems of connections heretofore generally used, the ratios of the heats are, assuming high heat equal to one—medium one-half, and low one-quarter heat. These ratios are not satisfactory in many cases in that low heat, which is ordinarily used just to maintain a boiling temperature, usually has a somewhat higher wattage input than is necessary. This results in excessive evaporation and waste of heat.

Furthermore, in certain cases it is desirable to obtain a high wattage input, such as 900 watts, for rapid preheating, and a low wattage input,—as low as 100 watts—to maintain a boiling temperature. Heretofore, a low wattage input has been obtained by providing an auxiliary resistance element for the heating unit formed of very fine wire. This element is fragile and has proven to be unsatisfactory, especially when high voltages, such as 230, are used.

This invention contemplates the provision of an improved heating system whereby relatively wide ratios are obtained between the high, low and medium heats in a simple, reliable and efficient manner, and with the use of two resistance elements.

In accordance with this invention, a heating unit is provided having two resistance elements. One resistance element is arranged to have a predetermined wattage input when operated on the maximum voltage between two main wires of the supply source, while the other is arranged to have a predetermined wattage input when operated on the reduced voltage between one of the main wires and the neutral wire. The combined

wattage inputs of the two resistance elements when thus operated provides the high heat desired. In order to obtain the medium heat, the two resistance elements are connected in parallel across one of the main wires and the neutral wire, while low heat is obtained by connecting the high voltage rating resistance element across one of the main wires and the neutral.

For a more complete understanding of this invention, reference should be had to the accompanying drawing in which Fig. 1 is a diagrammatic view illustrating a heating system arranged in accordance with this invention, and illustrating diagrammatically switching means provided to control the connections between the resistance elements of a heating unit and their supply source; and Figs. 2, 3 and 4 are views similar to Fig. 1, but illustrating the switching means in different controlling positions to provide different connections between the resistance elements and the supply source, whereby high, medium and low heats are produced respectively.

Referring to the drawing, this invention has been shown in one form, as applied to an electric heating system for hot plates and the like of an electric range, but it is to be understood that the invention has other applications. As shown in Fig. 1, the hot plate 10, shown diagrammatically, comprises two resistance elements 11 and 12.

The resistance elements 11 and 12 are provided with a suitable electrical supply source 13 shown as a three-wire electrical supply source having two main wires 13a and 13b and a neutral wire 13c. The voltage across the main wires 13a and 13b is double the voltage between either of the main wires 13a, 13b, and the neutral wire 13c. For example, the voltage between the main wires 13a and 13b may be 230 volts, while the voltage between either of the main wires 13a and the neutral wire will be 115 volts.

The resistance element 11 is so arranged that when it is connected to one of the main wires 13a, 13b and the neutral 13c, it will take a predetermined wattage input, while the resistance element 12 is so arranged that when it is connected to the two main wires 13a and 13b it will take a predetermined wattage input. For example, the resistance element 11 when connected between one of the main wires and the neutral, that is, on the 115 volt source, will have a 500 watt input, while the resistance element 12 will be arranged so that when it is connected across the two main wires on the 230 volt source, it will have an input of say 400 watts. As

pointed out previously, it is contemplated that when the two elements 11 and 12 are connected simultaneously to the supply source 13 so that the element 11 is connected to one of the main wires 13a, 13b and the neutral 13c, while the element 12 is connected to the two main wires 13a and 13b, the combined wattage input of the elements will provide a high rate of heat generation. As also pointed out, it is further contemplated that in order to obtain a medium heat the resistance element 11 will be connected, as before, to one of the outside wires 13a, 13b and the neutral 13c, while in this case, the resistance 12 likewise will be connected across one of the main wires and the neutral in parallel with the resistance 11. In order to obtain low heat, the resistance element 12, which is designed to take a predetermined wattage input when operated across the high voltage source 13a, 13b, will be connected across one of the main wires 13a, 13b and the neutral 13c.

More specifically, in the specific example given wherein the voltage between the main wires 13a and 13b is 230 and that between either main wire 25 and the neutral 13c is 115, and where the resistance element 11 has a wattage input of 500 when connected to the 115 volt source, while the resistance element 12 when connected to the 230 volt source has a wattage input of 400, 30 then when the two elements 11 and 12 are connected respectively to these sources, they will take a combined input of 900 watts, which in this case provides the high heat condition of the heating unit 10. When the two resistance 35 elements 11 and 12 are connected in parallel across one of the main wires 13a, 13b and the neutral 13c, that is to the 115 volt source, they will take a wattage input of 600 watts, which is the medium heat generated by the heating unit 40 10, and when the high voltage resistance element 12 alone is connected to the low voltage source across one of the main wires 13a, 13b and the neutral 13c it will have a wattage input of 100 watts, which provides low heat in the 45 unit 10. It will be observed, therefore, that the heating element 10 has a very large ratio between the low heat wattage input of 100 watts and the 900 watts input for the high heat operation of the unit. It will also be observed that 50 a very useful medium heat wattage input of 600 watts is provided.

The heating elements are controlled by means of a single multiple position manually operable control switch 14. This switch may have any 55 suitable construction, and is shown quite diagrammatically in the drawing. The switch has four controlling positions, an off position shown in Fig. 1, a high heat position shown in Fig. 2, a medium heat position shown in Fig. 3, and a low heat position shown in Fig. 4. The switch is provided with three movable contactors 15, 16, and 17. The contactor 15 cooperates with fixed contacts 15a and 15b; the contactor 16 with fixed contacts 16a and 16b; and the contactor 17 with fixed contacts 17a, 17b and 17c.

As shown in Fig. 1, when the switch is in its off position, neither one of the resistance elements 11 or 12 is connected with the supply 70 source 13. However, when the switch is rotated to its high heat position (Fig. 2) by moving it a quarter turn in the clockwise direction from its off position, the left hand end of the resistance element 11 will be connected to the 75 lower main wire 13b of the supply source 13

through the contactor 15, while its right hand end will be connected to the neutral wire 13c through the contactor 16. In this position of the switch, the left-hand end of the resistance element 12 will be connected with the main wire 5 13b of the supply source through the contactor 15 and its other end with the main wire 13a through the contactor 17. Thus, in the high heat position, the resistance element 11 is connected to the 115 volt source, while the resistance element 12 is connected to the 230 volt source. As pointed out previously, the wattage inputs of the two elements are thus combined so as to provide the high heat generation for the heating unit 10. When the switch is moved 10 15 a quarter turn from its position shown in Fig. 2 to its position shown in Fig. 3, it will connect the elements 11 and 12 to the supply source 13 to provide the medium heat. In this position of the switch, the left-hand ends of both resistance elements 11 and 12 are connected to the main wire 13b of the supply source through the contactor 15, while the right-hand ends of these elements are connected to the neutral wire 13c by means of the contactors 16 and 17 respectively. In other words, the two elements 11 and 12 are connected in multiple across the 20 25 115 volt source. When the switch is moved a quarter turn from its position shown in Fig. 3 to its low heat position shown in Fig. 4, the resistance element 11 is disconnected from the supply source, while the left-hand end of the resistance element 12 is connected to the main wire 13b through the contactor 15 and its right hand end is connected to the neutral wire 13c 30 through the contactor 17.

It is to be understood that the above figures with reference to the voltages of the supply source and the wattage inputs that the two elements 11 and 12 have respectively when connected to the low and high voltages of the supply source are merely illustrative, and that the elements 11 and 12 may have any suitable wattage inputs when operated respectively on the low and high voltages of the supply source, and that these voltages may be varied. It is to be noted, however, that irrespective of the wattage inputs that these elements take when connected to the two sources, the ratio between the low 40 45 wattage input for low heat and the high wattage input for high heat is materially increased over that obtained in the heating systems heretofore generally used. It is also to be noted that a medium heat wattage input intermediate 50 55 these low and high heat inputs has been provided which is more useful than the medium heat wattage inputs heretofore provided.

It is also to be understood that the resistance elements 11 and 12 may be supplied from two voltage sources of supply other than the three-wire system 13 shown in the drawing; thus, for example, the elements may be supplied from a three-phase, four-wire system wherein the voltage between two of the main wires provides 60 65 the high voltage source, while that between one of the main wires and the neutral provides the low voltage source.

While I have shown a particular embodiment of my invention: it will be understood of course 70 that I do not wish to be limited thereto since many modifications may be made, and I, therefore contemplate by the appended claims to cover any such modifications as fall within the true spirit and scope of my invention.

What I claim as new and desire to secure by Letters Patent of the United States, is:

1. An electrical heating system for a hot plate of an electric range and the like comprising a three-wire source having a relatively high voltage across two of said wires as compared with that across each of said two wires and the third wire, a single heat generating element for said hot plate comprising a pair of resistance elements, each having but two terminals and one arranged to take a predetermined wattage input when its two terminals are connected to said two wires and the other a predetermined wattage input when its two terminals are connected to one of said two wires and said third wire, a single multi-position switch controlling said resistance elements arranged in one position to connect simultaneously the two terminals of said first resistance element to said two wires and those of said second resistance element to one of said two wires and said third wire, whereby said predetermined wattage inputs are combined to produce a high heat generation for said hot plate, and in another position to connect only the two terminals of said first resistance element to one of said two wires and said third wire to produce a low heat generation for said hot plate.
2. An electric heating system for a hot plate of an electric range and the like comprising an electrical supply source having a relatively high and a relatively low voltage, a single heat generating element for said hot plate comprising a pair of resistance elements, each having but two terminals and one having a rating to take a predetermined wattage input when its two terminals are connected to said high voltage source and the other having a rating to take a predetermined wattage input when its terminals are connected to said low voltage, a single multi-position switch controlling said heat generating element arranged in one position to connect simultaneously the two terminals of said first resistance element to said supply source so that said high voltage is supplied to it and the two of said second resistance element to said supply source so that said low voltage is supplied to it,
- whereby said predetermined wattage inputs of said elements are combined to provide a high heat for said hot plate, in another position to connect the two terminals of each resistance to said supply source so that said low voltage is applied to both of them simultaneously to provide a medium heat for said hot plate, and in still another position to connect only the two terminals of said first resistance element to said supply source so that said low voltage is supplied to it to provide a low heat for said hot plate.
3. An electrical heating system for a hot plate and the like comprising a three-wire electrical supply source having two main wires and a neutral wire, the voltage between the main wires being relatively high as compared with that between each main wire and said neutral wire, an electrical heating element for said hot plate provided with a pair of resistance elements, each having but two terminals and one having a predetermined wattage input when its two terminals are connected to said two main wires and the other a predetermined wattage input when its two terminals are connected to one of said main wires and said neutral wire, and a single multi-position switch controlling said resistance elements arranged in one position to connect one terminal of each of said resistance elements to one of said main wires, the other terminal of said first resistance element to the neutral wire and the other terminal of said second resistance element to the other main wire to effect a high heat condition in said hot plate, in another position to connect one terminal of each of said resistance elements to one of said main wires and the other terminals of each of said elements to said neutral wire to effect a medium heat condition in said hot plate, and in still another position, to connect one terminal of said second resistance element to one of said main wires and its other terminal to said neutral wire to effect a low heat condition in said hot plate, said first resistance element being disconnected from said supply source in this position of said switch.

JOHN C. SHARP.
